ATTORNEY.

UNITED STATES PATENT OFFICE.

DAVID DUNDAS, OF GLASGOW, SCOTLAND.

SHIP'S SIDE LIGHT OR WINDOW.

1,357,625.

Specification of Letters Patent.

Patented Nov. 2, 1920.

Application filed June 3, 1920. Serial No. 386,324.

To all whom it may concern:

Be it known that I, DAVID DUNDAS, Hunter Street, Whiteinch, Glasgow, Scotland, a subject of the King of Great Britain, have invented certain new and useful Improvements Relating to Ships' Side Lights or Windows, of which the following is a specification.

This invention relates to ships' side lights or windows and its object is to provide a simple gear whereby the window can be easily operated.

Under this invention ships' side lights or windows are provided with means for opening and closing same, said means being characterized by a lazy-tongs or like arrangement of levers capable of being operated by screw or equivalent gear, means being also provided for balancing the weight 20 of the window and thereby facilitating the opening and closing operations.

The means fitted in connection with the levers for balancing the weight of the window and facilitating the opening and closing operations preferably consist of springs or their equivalent fitted in connection with the levers.

There is also provided in connection with the lazy-tongs arrangement of levers and the operating gear therefor, guides whereby the lazy-tongs motion is kept in a parallel line to the path of the window.

In order that my said invention may be properly understood I have hereunto appended an explanatory sheet of drawings whereon, by way of illustration or example, one embodiment of the invention is shown.

On the drawings:—

Figure 1 is a front view of a side light or window, as constructed under this invention, and

Fig. 2 is a side view thereof, partly in section but showing a slightly modified arrangement of levers c.

Referring to the drawings:—

In carrying out the invention the window sash a is slidably fitted within a frame b and can be raised and lowered, as desired, by means of a lazy-tongs arrangement of 50 levers c operable by means of a screw spindle d which, in turn, can be rotated by means of bevel gear e operable by a suitable handle or hand lever f. In order to balance the weight of the window a and thereby facilitate the raising operation one

or more springs g are provided in connection with the lazy-tongs levers c.

As illustrated at Fig. 1, the lazy-tongs arrangement of levers c, comprises two pairs of cross levers 1, 2, jointed together at h, i, the upper ends of the top pair 1 being connected by means of links j, to the window sash a while the lower ends of the bottom pair 2, are connected by links k to a base plate or bracket l.

Fitted on the one pair of levers 2 is an internally screwed socket m while on the other pair of levers 1, is a collar or guide n through which the screwed spindle d passes. By making the spindle d pass 70 through the socket m and the collar or guide n, secured to the levers c, the motion of said levers is kept in a true parallel line to the path of movement of the window a.

The lower end of the screwed spindle d 75 works in a bearing o in the base plate or bracket l and its upper end has fitted to it one of the bevel wheels of the bevel gear e, while the other wheel of the gear is mounted on a spindle p which passes 80 through a cover plate or guard q fitted to or forming part of the window frame b. The end of the spindle p is squared or otherwise formed for the reception of the operating handle or lever f, which can be removed when not required.

The springs g for facilitating the opening and closing operations are fitted at the joints r of the pairs of levers 1, 2, a suitable cup or socket or such like s being provided at each joint for the reception of the ends of the springs so as to retain same in the operative position. The springs g are so arranged, and their number is such as to balance the window a at any pre-determined position.

The number of pairs of levers c may be varied, as desired, in accordance with the length of the window a, the amount of travel of the screwed spindle d and the 100 available width into which the lazy-tongs have to go when the window is pulled down. There may be as many pairs or sections as will give the easiest motion and the least wear to the moving parts.

In Fig. 2 four pairs of levers c are shown, as indicated by the numerals 1, 2, 3 and 4, in place of two pairs, as illustrated in Fig. 1, but the construction is otherwise the same.

At the lower end of the spindle d where 110

it enters the bearing *o* of the bracket *l* a cushion spring *v* or its equivalent may be provided. It surrounds the spindle *d* while its lower end bears on the bracket *l* its object being to act as a stop for the window *a* when lowered to its full extent and to prevent the socket *m* being over-run.

By rotating the bevel gear the spindle is rotated and the cross levers are moved to raise or lower the window on the well known lazy-tongs principle, the weight of the window being balanced in any position by suitable springs connected to the ends of the jointed levers, as described.

15 The frame *b* of the window *a* may have a rubber cushioning strip *t* inserted in it against which the window can be pressed by means of pinching screws or the like *u* so as to force the window sash tightly against the 20 rubber seating thereby preventing rattling and also ingress of water.

Having now fully described my invention what I claim and desire to secure by Letters Patent is:—

25 1. In combination with sliding window, an extensible support of lazy-tongs nature therefor, means for operating the lazy-tongs to open and close the window and means fitted in connection with the lazy tongs for 30 balancing the weight of the window.

2. In combination with sliding window, an extensible support of lazy-tongs nature therefor, means for operating the lazy-tongs to open and close the window and spring 35 means fitted in connection with the lazy-tongs for balancing the weight of the window.

3. A ship's side light or sliding window having opening and closing means comprising 40 a lazy-tongs arrangement of levers fitted in connection with the window sash, sockets carried by the lazy-tongs levers, a screw spindle engaging the sockets, gearing for rotating the spindle, and means for operating 45 said gearing.

4. A ship's side light or sliding window

having opening and closing means comprising a lazy-tongs arrangement of levers fitted in connection with the window sash, sockets carried by the lazy-tongs levers, a screw 50 spindle engaging the sockets, bearings for the spindle, gearing for rotating the spindle in its bearings, springs in connection with the lazy-tongs levers for balancing the weight of the window, and a handle for operating the gearing.

5. A ship's side light consisting of a window frame with a resilient lining, a window 55 slidable within the frame and means whereby the window can be forced tightly against said resilient lining, in combination with means for opening and closing the window comprising a lazy-tongs arrangement of levers pivoted at one end to the window and at the other end to a fixed bearing, sockets carried by the levers, a screw spindle rotatably mounted in said bearing and engaging said 60 sockets, gears carried by the window frame for rotating the spindle and a lever for operating said gears.

6. A ship's side light consisting of a window frame with a resilient lining, a window 65 slidable within the frame and means whereby the window can be forced tightly against said resilient lining, in combination with means for opening and closing the window comprising a lazy-tongs arrangement of levers pivoted at one end to the window and at the other end to a fixed bearing, sockets carried by the levers, a screw spindle rotatably 70 mounted in said bearing and engaging said sockets, gears carried by the window frame for rotating the spindle, a lever for operating said gears, and a cushioning stop for the 75 window located on the screw spindle.

In testimony whereof I affix my signature in presence of two witnesses.

DAVID DUNDAS.
